ELECTRICAL APPARATUS

Cyril William Brown, Wallington, England, assignor to Radio Patents Corporation, a corporation of New York

Application March 6, 1942, Serial No. 433,620
In Great Britain March 14, 1941

6 Claims. (Cl. 179—171)

This invention relates to arrangements for coupling the output end of a transmission line into a thermionic valve amplifier.

The principal object of the invention is to provide a means of terminating a transmission line at its output end in an impedance which offers a low resistance to alternating current and which offers a higher resistance to direct current.

In the arrangement according to the invention the output end of the transmission line is connected as a cathode load common to the control grid and anode circuits of a valve, the control grid of this valve being maintained at substantially zero signal potential and the anode load impedance being of low value compared with the anode impedance of the valve.

By this arrangement the transmission line is terminated in a resistance to direct current equal to the direct current resistance of the valve and it is terminated in a resistance to alternating current equal to the reciprocal of the sum of (a) the mutual conductance of the valve and (b) the reciprocal of the anode impedance of the valve. The reciprocal of the anode impedance of the valve will generally be negligible in comparison with the mutual conductance of the valve, so that the resistance to alternating current becomes equal to the reciprocal of the mutual conductance of the valve.

If it is desired to avoid having direct current circulating in the transmission line, or if a resistance to alternating current lower than the reciprocal of the mutual conductance of the valve is required, a substantially purely resistive impedance may be connected across the output end of the transmission line. This further resistance will appear in parallel with both the direct current and the alternating current resistance values above mentioned.

In the accompanying drawings, Figures 1 and 2 are circuit diagrams showing alternative arrangements for coupling of the output end of a transmission line into the circuit of a thermionic valve, these arrangements being suitable for the transmission of television signals but without the direct current component which represents average picture brightness. Figure 3 shows another arrangement, but in which the direct current component of the signal is transmitted. Figure 4 shows a push-pull arrangement in which the direct current component is not transmitted.

In the arrangement shown in Figure 1, the triode output valve 1 of a pre-amplifier of television signals is arranged as a cathode follower developing the output signals across its cathode

load, which comprises resistance 2 and small series inductance 21 to compensate for stray shunt capacities, so that the resultant cathode load is substantially purely resistive at all frequencies within the frequency spectrum of the signals to be transmitted. The transmission line comprising conductors 3, 4, which may be parallel or concentric, is connected across cathode load 2, 21 and carries the signals to the main amplifier, the first stage of which is the circuit of pentode valve 5. Line 4 is connected to the cathode of pentode 5 while line 3, being earthed at the input end, is maintained at zero signal potential. The control grid of pentode 5 is maintained at zero signal potential by coupling to line 3 through condenser 6. The control grid bias is derived through grid leak resistance 7 from potentiometer 8, which is connected across a high potential source connected to line 3 at its negative end. The screen grid of pentode 5 is maintained at the signal potential of the cathode by coupling condenser 9 and derives its supply potential from potentiometer 8. The suppressor grid is maintained at cathode potential by the conventional direct connection.

The anode load of pentode 5 comprises resistance 10, and in series therewith a small inductance 11 to compensate for stray capacities. The output signals developed across anode load 10, 11 are passed through coupling condenser 12 to output terminal 13. The anode current of pentode 5 circulates in transmission lines 3, 4, passing through cathode load 2, 21, in parallel with that of triode 1.

It is desirable that the transmission line should be correctly matched with at least one of the terminating impedances.

If the characteristic impedance of transmission line 3, 4, is 100 ohms, it will be correctly matched at the output end if the mutual conductance of pentode 5 is 10 milliamps. per volt, the anode impedance of pentode 5 being high in comparison with 100 ohms.

In order to achieve the high mutual conductance of 10 milliamps. per volt, it may be necessary in practice for the pentode represented at 5 to be made up of two similar pentodes connected in parallel.

If resistance 2 is of high value, the transmission line may similarly be matched at the input end by the employment for valve 1 of a valve, or a pair of valves in parallel, having a mutual conductance of 10 milliamps per volt. If, however, the anode impedance or the value of resistance 2 is comparable with the characteristic impedance

of the transmission line, the necessary value of mutual conductance for matching will be accordingly lowered.

If the anode impedance of pentode 5 is about 500,000 ohms, the value of anode load resistance 10 may be about 10,000 ohms.

The time constant of the input circuit will be determined by the values of resistance 7 and condenser 8. If these are 1 megohm and 1 microfarad respectively, the time constant will be 1 second.

In the arrangement illustrated in Figure 2, across the output end of transmission line 3, 4 there is connected an impedance comprising a resistance 14 and in series therewith a small inductance 15 for compensating for stray capacities. The input valve of the main amplifier is here shown as a triode 20 instead of a pentode. The control grid bias is shown as derived from grid leak resistance 22 from a tapping on resistance 14. As the anode impedance of a triode is very much lower than that of a pentode, resistance 10 must be of low value and the inductance 11 of Figure 1 will normally be unnecessary and is, therefore, omitted. It may be necessary to take into account the anode impedance of triode 20 as well as its mutual conductance for the purpose of calculating the input impedance presented to transmission line 3, 4.

The value of resistance 14 may be selected in order to correct the matching between the transmission line and the resistance for alternating currents presented by the circuit of pentode 5. Alternatively, it may be selected with regard to the value of resistance 2 so that no direct current will circulate through the transmission line 3, 4. This will be achieved if the direct current potential drop across resistance 14 due to the anode current of valve 20 is equal to that across resistance 2 due to the anode current of valve 1. If the anode current of valve 1 is 5 milliamps, the value of resistance 2 may be 10,000 ohms. Assuming that the anode current of pentode 5 is 20 milliamps., resistance 14 may then be 2,500 ohms, so that the potential drops at both ends of transmission line 3, 4 will be 50 volts.

In the arrangement shown in Figure 3, in order to transmit the direct current component of the signal, the control grid of pentode 5 is directly connected to a point on potentiometer 31 which, in this case, should be of low resistance. The part thereof between the control grid tapping and line 3 may, for example, be 500 ohms, so as to be of low value in comparison with the reactance due to grid-cathode capacity at the highest frequencies to be handled. The screen grid of pentode 5 is coupled by condenser 32 to the line 3 of zero signal potential, instead of to the cathode, because its D. C. connection is to the point of low potential, not to the cathode, and it is desired that the circuit should respond in the same way to D. C. and A. C. signals. The effect of inserting the signal voltage from the transmission line between cathode and screen grid is small, because the screen grid has only a small mutual conductance. The output terminal 43 is directly connected to the anode instead of being connected through a coupling condenser.

In the arrangement shown in Figure 4, the output valves 1, 41 of the pre-amplifier are connected in push-pull, and the input valve 5, 48 of the main amplifier are also in push-pull. Neither of the conductors 4, 44 of the transmission line is earthed, but the centre points of the cathode loads of both pairs of valves are earthed.

The arrangement is not intended for transmission of the direct current component of the signals and the control grids are, therefore, maintained at zero signal potential by a coupling condenser 6. Control grid bias is derived from a tapping on cathode load resistance 14 in the same manner as in Figure 2. The screen grids are maintained at zero signal potential by condenser 8 and the screen grid currents are supplied from a high potential source through resistance 49.

The output circuits are similar to those of pentode 5 in Figure 1, and the push-pull output potential is developed between terminals 13, 43.

I claim:

1. An electrical system comprising a transmission line having high potential and low potential input and output terminals, a pair of vacuum tube amplifiers each having a cathode, a grid and a plate, a cathode load resistance common to the grid and plate circuits of the first tube for feeding the input of said line, the high potential input terminal of said line being connected to the cathode of the first tube and the high potential output terminal of said line being connected to the cathode of the second tube, a connection for signal currents from the grid of the second tube to the low potential output terminal of said line, whereby said line forms an input impedance common to the grid and plate circuits of said second tube and said resistance provides a cathode return for the direct current of said second tube, the reciprocal of the mutual conductance of each of said tubes substantially matching the characteristic impedance of said line, and a plate load resistance for said second tube.

2. An electrical system comprising a transmission line having high potential and low potential input and output terminals, a pair of vacuum tube amplifiers each having a cathode, a grid and a plate, a cathode load resistance common to the grid and plate circuits of the first tube for feeding the input of said line, the high potential input terminal of said line being connected to the cathode of the first tube and the high potential output terminal of said line being connected to the cathode of the second tube, a capacitive circuit connection from the grid of said second tube to the low potential output terminal of said line, whereby said line forms an input impedance common to the grid and plate circuits of said second tube and said resistance provides a cathode return for the direct current of said second tube, the reciprocal of the mutual conductance of each of said tubes substantially matching the characteristic impedance of said line, and a plate load resistance for said second tube having a value low compared with the plate impedance of said second tube.

3. An electrical system comprising a transmission line having high potential and low potential input and output terminals, a pair of vacuum tube amplifiers each having a cathode, a grid and a plate, a cathode load resistance common to the grid and plate circuits of the first tube for feeding the input of said line, the high potential input terminal of said line being connected to the cathode of the first tube and the high potential output terminal of said line being connected to the cathode of the second tube, a connection for direct current from the grid of said second tube to the low potential output terminal of said line, whereby said line forms an input impedance common to the grid and plate circuits of said second tube and said resistance provides a cathode return for the direct current of said second tube,

the reciprocal of the mutual conductance of each of said tubes substantially matching the characteristic impedance of said line, and a plate load resistance for said second tube having a value low compared with the plate impedance of said second tube.

4. An electrical system comprising a transmission line having high potential and low potential input and output terminals, a pair of vacuum tube amplifiers each having a cathode, a grid and a plate, a cathode load resistance having a value high in comparison to the characteristic impedance of said line and common to the grid and plate circuits of the first tube for feeding the input of said line, the high potential input terminal of said line being connected to the cathode of the first tube and the high potential output terminal of said line being connected to the cathode of the second tube, a connection for signal currents from the grid of said second tube to the low potential output terminal of said line, whereby said line forms an input impedance common to the grid and plate circuits of said second tube and said resistance provides a cathode return for the direct current of said second tube, the reciprocal of the mutual conductances of each of said tubes substantially matching the characteristic impedance of said line, and a plate load resistance for said second tube having a value low compared with the plate impedance of said second tube.

5. An electrical system comprising a transmission line having high potential and low potential input and output terminals, a pair of vacuum type amplifiers each having a cathode, grid and plate, a cathode load resistance having a value high compared with the characteristic impedance of said line and common to the grid and plate circuits of the first tube for feeding the input of said line, the high potential input terminal of said line being connected to the cathode of said first tube and the high potential output terminal of said line being connected to the cathode of

said second tube, the plate impedance of said second tube being high compared with the characteristic impedance of said line, a connection for signal currents from the grid of said second tube to the low potential output terminal of said line, whereby said line forms an input impedance common to the grid and plate circuits of said second tube and said resistance provides a cathode return for the direct current of said second tube, the reciprocal of the mutual conductance of each of said tubes substantially matching the characteristic impedance of said line, and a plate load resistance for said second tube having a value small compared with the plate impedance of said second tube.

6. In combination, a transmission line having high potential and low potential input and output terminals, a first vacuum tube amplifier having at least a cathode grid and plate, a second vacuum tube amplifier having at least a cathode, a control grid, a screen grid and a plate, a cathode load resistance having a value high compared with the characteristic impedance of said line and common to the grid and plate circuits of said first tube for feeding the input of said line, the high potential input terminal of said line being connected to the cathode of the first tube and the high potential output terminal of said line being connected to the cathode of the second tube, a connection for signal current from the grid of said second tube to the low potential output terminal of said line, whereby said line forms an input impedance common to the grid and plate circuits of said second tube and said resistance provides a cathode return for the direct current of said second tube, the reciprocal of the mutual conductance of each of said tubes substantially matching the characteristic impedance of said line, and a plate load resistance for said second tube having a value low compared with the plate impedance of said second tube.
